Specification of Letters Patent.

Patented Oct. 14, 1919.

Application filed April 25, 1919. Serial No. 292,738.

To all whom it may concern:

Be it known that I, LEWIS SYKES, a citizen of the United States, residing in the city and county of Camden, State of New Jersey, have invented a new and useful Piston-Rod and Toggle for Motors, Pneumatic Drills, Air-Tools, and the like, of which the following is a specification.

My invention relates generally to a novel 10 construction of a pneumatic drill, air tool or similar implement, and relates more particularly to a novel construction of a piston rod and means for uniting the ends of the piston rod with the inside and outside toggles which coact with the crank shaft, the opposite end of the piston rod being connected with the piston in a novel and durable manner.

In the devices of the prior art with which 20 I am very familiar, it has heretofore been the practice to employ a ball and socket connection between the piston and the contiguous end of the piston rod, while the opposite end of the piston rod is secured in 25 position by a hinged toggle, which in practice I have found to be an unsatisfactory construction, since the hinge pins shear and the reduced section of metal surrounding said hinge pins breaks down, so that the 30 entire strain is thrown upon the tapered end of the toggles and the binding nut, which connects the two halves of the toggle. This binding nut has heretofore been made of steel, heat treated to a certain degree with 35 a straight internal thread to engage the male taper thread on the end of the toggle.

I have found that the practice of forcing 40 this soft, straight threaded nut over the tapered end of the toggles, thereby stretching the metal in the nut anywhere from 1/64 to 1/16 of an inch, is objectionable, since by the time this nut is only half way home, the metal in the nut is fatigued beyond repair, and the mechanism referred to 45 will not in practice withstand the continued wrecking force and vibration to which it is subjected for any length of time.

Furthermore, in the structure of the prior 50 art, the threaded split clamping nut, which is intended for a lock and clamp combined, instead of clamping the piston rod, has a tendency to unseat the binding nut, already fatigued, and allows the piston rod to become loose and the intermittent impulses

of air against the face of the piston force 55 the piston rod back and forth against a little shoulder employed, which in a very short time wears, and for this reason is very unsatisfactory.

At the ball end of the piston rod, I have 60 experienced considerable trouble with breakage below the ball, since at this point the diameter of the piston rod is reduced to allow the ball to rotate in the ball socket 65 far enough to suit the throw of the crank, and in some instances, I have found that the ball becomes disengaged from the socket and the effective operation of the drill is consequently impaired.

To remedy the foregoing objectionable 70 features, I have devised a novel construction of piston rod, which is provided with a T-head at one end and a reduced tapered neck and an outer head at the other end, the 75 entire outer area of said latter head taking up the thrust of the entire rod in both the inside and outside toggles, whereby the piston rod is prevented from wear and the extremity of said outer head has an eccentric 80 pin, which interlocks with a seat in the co-acting toggle member, whereby the piston rod is prevented from improper rotation.

In my present invention, I connect the 85 piston end of the rod to the piston, in lieu of the objectionable ball and socket connection referred to, by means of a T-end connection rotating on a hardened steel pin 90 arc welded into a suitable support, made from a punched and pierced blank, bent to shape, said support being assembled and spot-welded or riveted upon the inner face 95 or bottom of the piston, the swing of the piston rod being limited only by the diameter of the bore of the piston.

In lieu of the objectionable binding nut 100 and threaded split clamping nut heretofore referred to, I employ in place of the soft, straight, internally threaded nut of the prior art referred to, a reinforced, hardened, internally straight-threaded nut which has 105 elongated walls and a taper seat or cavity therein, the walls of which seat diverge outwardly so as to engage the correspondingly contiguous tapered walls of the toggle members, my novel binding nut being of such 110 form and dimension that when it is rotated upon the threaded portion of the connecting rod, the coacting surface of its inner tapered

walls will tighten and snugly engage with the tapered extension of the toggle members so that considerable force can be exerted in tightening up these parts without damage or undue stretching of the metal which is also very important in this connection and in addition my novel binding nut when properly tightened with respect to the piston rod and coacting toggle members will not tend 10 to work loose even under the excessive vibration, jar and abuse to which tools of this character are, as is well known, subjected.

In the foregoing novel construction of piston rod, together with its manner of attachment to the piston and to the inside and outside toggles, I have devised a construction wherein the binding nut will not work loose and the piston rod is locked against rotation with respect to its coacting 15 toggle and which will be found to be very rigid and durable for the purpose intended and which will withstand the hard usage to which implements of this character are subjected in shipyards, boiler plants, structural 20 iron works and the like, since the operators of these implements are very frequently unskilled workmen, and it is important in order that the maximum amount of work be accomplished with air tools of this general 25 character, that the same be constructed in a durable and efficient manner, particularly the connections common to the piston, piston rod and inner and outer toggles to which my present invention particularly relates.

For the purpose of illustrating my invention, I have shown in the accompanying drawings certain forms thereof which are at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a vertical, sectional view of an air tool or pneumatic drill, embodying my invention, showing particularly my novel construction of piston rod, inside and outside toggles, and the manner of securing the T-end of the piston rod to the piston.

Fig. 2 represents, on an enlarged scale, a plan view, the piston and T-head being shown in section, and the inside and outside toggles in elevation.

Fig. 3 represents a side elevation of Fig. 2, the piston and binding nut being shown in section and the toggles in side elevation.

Fig. 4 represents a plan view, partly in section, of my novel construction of piston rod.

Fig. 5 represents a plan view of a blank

from which the connection for securing the piston rod to the piston is formed.

Fig. 6 represents a connecting plate common to the T-end of the piston rod and piston, the same being struck up from the blank 70 seen in Fig. 5.

Fig. 7 represents a section on line 7—7 Fig. 3.

Fig. 8 represents a perspective view of the 75 inside toggles in detached position.

Fig. 9 represents a perspective view of the outside toggles in detached position.

Fig. 10 represents a perspective view of the valve actuating eccentric employed, and

Fig. 11 represents a perspective view of 80 the upper portion of the crank shaft coacting with said eccentric.

Similar numerals of reference indicate corresponding parts.

Referring to the drawings. 85

In the pneumatic drill or air tool 1 or similar implement to which my invention is applicable, I have illustrated one standard type of drill, in which 2 designates the casing, 3 the piston cylinders having the 90 pistons 4 therein, 5 the crank shaft having its lower portions provided with the bearings 6 and 7, and its upper journal 8 provided with the bearings 9.

10 and 11 designate gearing whereby 95 power is transmitted to the spindle 12 for actuating a drilling, reaming or other tool. 13 designates the valve actuating eccentric having the broached hole 14 therein, which is driven by the parallel flat or driving faces 100 14^x on the upper end 15 of the crank shaft 5, said eccentric being detachable in a vertical direction from said driving faces and actuating the eccentric strap 16, which is connected to the pin 17 of the valve 18. 105

With the exception of the construction of the eccentric and its manner of actuation and connection with the coacting driving faces 14^x, best seen in Figs. 1, 10 and 11, which form the subject-matter of a contemporaneously pending application filed by me, the above referred to elements are of standard construction and require no further descriptions, it being understood that the valve 18, controls through suitable ports and passages the admission and exhaust of the motive fluid to and from the pistons 4, the valve being actuated by the eccentric 13, and the reciprocations of the pistons 4, effecting the rotation of the crank shaft 5, 115 whereby power is transmitted by the gearing 10 and 11 to the spindle 12 through the medium of the connecting rods and toggle connections therefor which constitute the novel features of my present invention 120 and will now be described in detail after a brief reference to the prior art.

The inside and outside toggles in connection with the piston rod and piston of the prior art, are in practice too light and 130

flimsy, the hinges being connected by hinge pins which shear and in addition the reduced section of metal surrounding the hinge pins breaks down, whereby the entire strain is then thrown onto the taper threaded end of the toggles, and the binding nut, which connects the two halves of the toggle. This binding nut of the prior art is made of steel, heat-treated to a certain degree with a practically straight internal thread, to engage the male taper thread on the end of the toggle, and I have found that the practice of forcing this soft, straight threaded nut over the taper threaded end of the toggles thereby stretching the metal in the nut anywhere from $1/64''$ to $1/16''$ is very objectionable, since by the time the nut is only half way home, the metal in the nut is fatigued beyond repair, and this mechanism will not in practice withstand the continued wrecking force and vibration to which it is subjected. In the case of the threaded split clamping nut of the prior art, which is intended for a lock, and clamp combined, this part, instead of checking the binding nut, and clamping the piston rod has in practice a tendency to unseat the binding nut already fatigued, and allows the piston rod to become loose and the intermittent impulses of air against the face of the piston forces the rod back and forth against a little shoulder which is only $1/32''$ and which in a short time wears and for this reason is very unsatisfactory.

To obviate the foregoing objections, I have devised a novel construction of a piston rod and a novel manner of securing the end of said rod to the piston, the opposite end of said piston rod terminating in an eccentric pin which interlocks with a novel construction of inside and outside toggles, which features constitute my present invention and will now be described in detail.

19 designates my novel construction of piston rod, the same comprising the piston rod proper 20, having at its piston end the enlarged head or T-end 21, having the transverse hole or bearing 22 therethrough, which rotates or oscillates on the hardened hollow steel pin 23. The ends 29 of said pin 23 are arc-welded into the holes 24 of a suitable support, as the ears 25, which are struck up from or integral with the plate or body portion 26, seen in Figs. 5, 6 and 7.

In forming the support for the T end 21 of the piston rod, I take a suitable circular blank, as seen in Fig. 5, and form the cuts 27 and the holes 24 in the ends 25 therein, preferably by a single operation, as is apparent to those skilled in the art. The ears 25 are then deflected at right angles to the body 26 to form the construction seen in Figs. 1, 6 and 7, and the body portion 26 is either riveted to the inner face or bottom of

the piston 4, as indicated at the points 28 in Fig. 7, or it may be spot-welded thereto, if desired.

By arc-welding the ends 29 of the pin 23 into the ears 25, as seen in Figs. 2, 3, and 7, 70 a very rigid and efficient unitary structure is produced when the parts are assembled, it being of course understood that the pin 23 is passed through the bearing 22 in the T-head 21 before its ends 29 are arc-welded. 75

The crank shaft end of the piston rod 20 has the reduced tapered neck 30 terminating in the head 31, and special attention is called to the fact that the thrust is taken up by the entire end area 32 of the piston rod 80 in both the inside and outside toggles, in conjunction with the shoulders 33, as will be best understood from Fig. 1.

The detailed construction of the toggle members will be best understood from Figs. 85 2, 3, 8 and 9, which will now be described.

34 designates the inside toggle, see Fig. 8, which is composed of the members 35 and 36, which carry the bearings 37 and 38 respectively, which engage the juxtaposed 90 portions of the crank shaft 5, the member 35 having the tongue 39 engaging and interlocking with the groove 40 of the member 36.

The extension 41 of the member 36 has a seat 42 therein to receive the head 31 of the piston rod 20, it being noted that the end area 32 of the piston rod 19 abuts against the wall 43, while the neck 30 occupies the space 44 and the piston rod proper the bore or space 45, the exterior wall of the latter being tapered as indicated at 46. The extension 47 of the upper toggle member is similarly internally chambered or constructed, as already described, as will be understood from the right of Fig. 3, and terminates in 100 the tapered member 48, so that the tapered portions 46 and 48 of the parts when assembled as seen at the right of Fig. 3, are engaged by the binding nut 49, which is threaded upon the piston rod and is preferably a reinforced, hardened, tapered, internally threaded nut, which has the internal conical seat or tapered walls 50 extended long enough to form an elongated bearing for the tapered extensions 46 and 48. 110

The binding nut 49 is of such form and dimension that considerable force can be exerted in tightening up the parts engaged thereby, without damage or undue stretching of the metal, which is a very advantageous feature in this connection. 120

51 designates the outside toggle seen in Fig. 9, which is composed of the two members 52 and 53. The member 52 has the curved arms 54, which have the internal concave portions 55, which fit over the convex members 37 (see Fig. 8), and said arms terminate in the hooks having the inwardly extending walls 56, which when the parts are assembled engage and interlock with the 130

bottom of the outwardly projecting terminal lips 57 of the lower arms 58, which have the interior concave portions 59, which engage the convex extensions 38. The tapered extension 60 of the member 53 has the recess 61 for the head 31 of its piston rod, the entire end area 32 of said head exerting a thrust on the wall 62, while the neck 30 occupies the space 63, and the piston rod 10 proper is seated in the space or concavity 64, the outer wall of which is tapered as at 65. The tapered extension 66 of the member 52 is internally similarly constructed, as will be understood from Fig. 3, and is tapered as 15 at 67, so that the parts when assembled are securely locked by the binding nut 49, as seen at the left of Fig. 2, the dowel pins 69 interlocking with the seats 68 in the member 60.

20 The members of the inside toggle 34 may be provided with a port or ports 70 for lubrication, and the pin 23 may also be provided with lubricating ports 71.

I desire to call especial attention to the 25 fact that my novel binding nut 49 is threaded only at one exterior, as indicated at 73, said threaded portion engaging the threaded portion 74 of the piston rod or connecting rod 19, and that by reason of the novel construction of the internal conical seat formed 30 by the tapered walls 50, when said nut is forced upon the elongated taper or conical extensions of the contiguous toggle members, an exceedingly tight and efficient joint 35 is formed between said nut and the contiguous toggle members, and by having said nut in threaded engagement with the piston rod, the parts when assembled as seen in Figs. 1, 2 and 3 will be effectively locked in assembled position.

I also desire to call especial attention to the function of the eccentric locking pin 75 of the piston rod 19, which when the parts are assembled interlocks with either the seat 45 76 seen in Fig. 9 or the seat 77 seen in Fig. 8 of the appropriate toggle member, the object of said eccentric locking pin being to prevent the piston rod and piston from improper rotation during the reciprocations of 50 the motor.

It will be further apparent that when the T-head 21 of the piston rod is assembled upon its hardened steel pin, which I make 55 preferably hollow for the purpose of lightness or lubrication, and the ends 29 of said pin have been arc-welded or acetylene welded and the plate 26 spot-welded or riveted to the piston 4, as seen in Figs. 2 and 3, a very light, rigid and durable structure is produced wherein the liability of breakage and undue wear are reduced to a minimum.

If desired, I may employ on the ends of the hardened steel pin 23 the washers 78 seen in Figs. 2 and 3, which may be secured 60 in position in any suitable manner.

By constructing the piston rod 20 with the enlarged T-head 21 at its piston end, I provide increased strength at the point where it is most needed, and by collocating the head 31 of the piston rod with the toggles, so that its entire end area 32 abuts directly against the contiguous wall, as 43, of the inside toggles, and 62 of the outside toggles, it will be evident that the entire longitudinal thrust of each piston rod is 70 correctly and effectively applied at the proper point of each of the toggles, and there will be no undue wear at the contiguous portions of the piston rods and toggles, as is the case in the prior art constructions 75 I have heretofore referred to.

By making the tapered extensions 46, 48, 65 and 67 of the inside and outside toggle members, so that the same are of the form of a truncated cone when assembled, and by 80 elongating the walls of the binding nuts 49 so as to obtain an elongated bearing between the contiguous surfaces of said binding nut and the toggle members, it will be seen that an ample bearing surface is formed to enable 85 the binding nuts to frictionally engage the contiguous portions of the toggle members, so that there will be no liability of any wear or loosening action upon the binding nuts.

By making the inner bores of the extensions of both the inner and outer toggles to conform to the parts 33, 30, 31 and 43 of the piston rod 20 (see Fig. 4), the toggle members when assembled with respect to their piston rods, interlock properly and effectively therewith.

By constructing the outer members of the outer toggles with the interlocked hooked members, best seen in Figs. 3 and 9, the expense of drilling and inserting pins in the 105 hinged ends of the prior art devices above referred to, is entirely dispensed with, and in addition, the interlocked hooked members strengthen and reinforce the outer terminals of the arms of the outside toggles at a point 110 where they have heretofore been weakened, so that the toggle connections when assembled, as seen in Figs. 1, 2 and 3, constitute a reliable and durable driving connection 115 common to the crank shaft and the piston rods and their adjuncts. By making the binding nut 49 of a thickened or reinforced hardened internally tapered construction, the same will possess the requisite strength, so that considerable strength can be exerted 120 in tightening up the coacting parts, so that they will not be liable to become disconnected during the reciprocations of the piston and the rotation of the crank shaft.

It will be understood that in practice, two 125 pairs of angularly disposed cylinders and pistons, and two pairs of the inside and outside toggles, are employed, whose structure and manner of assembling will be apparent from Figs. 1, 2, 3, 8 and 9.

While I have shown my invention as especially applicable to a pneumatic drill, it will be understood that I do not limit myself thereto, as the broad principles of my invention are applicable to other types of motors and to any construction wherein a rigid and durable connection is required between the piston or motor, its piston rod and the coacting toggle elements which engage 10 the crank shaft of a motor or the like where the pistons are of small size, and where it is essential that a rigid and durable connection be had intermediate the pistons and the crank shaft to effect the rotation of the 15 latter.

It will be clearly understood from Figs. 1, 2 and 3, that when the eccentric locking pin 75 is interlocked with its recess in its appropriate toggle, that not only are the 20 piston rod and piston prevented from improper rotation, but, in addition, when the binding nut 49 is tightened up, there can be no rotation of the piston rod during and after such tightening of the binding nut, 25 whereby all the parts are positively and durably retained in assembled operative condition.

It will now be apparent that I have devised a novel and useful construction of a 30 piston rod and toggles for motors, pneumatic drills, air tools and the like, which embodies the features of advantage enumerated as desirable in the statement of the invention and the above description, and while 35 I have, in the present instance, shown and described a preferred embodiment thereof which will give in practice satisfactory and reliable results, it is to be understood that the same is susceptible of modification in 40 various particulars without departing from the spirit or scope of the invention or sacrificing any of its advantages.

Having thus described my invention, what I claim as new and desire to secure by Letters Patent, is:

1. In a machine of the character stated, a piston rod having a portion intermediate its ends threaded and terminating in a longitudinally extending eccentric terminal 50 locking pin, located out of alinement with the longitudinal axis of said rod.

2. In a machine of the character stated, a piston rod having a T head at one end with a hole therethrough, and an eccentric 55 terminal locking pin at its other end.

3. In a machine of the character stated, a piston rod having a T head at one end with a hole therethrough, a threaded portion intermediate its ends, and an eccentric 60 terminal locking pin at its other end.

4. In a machine of the character stated, a piston rod having a portion thereof intermediate its ends threaded, a reduced neck near one of its ends and a head at said 65 latter end terminating in a longitudinally

extending eccentric locking pin, the latter being located out of alinement with the longitudinal axis of said piston rod.

5. In a machine of the character stated, a piston rod having a portion thereof intermediate its ends threaded, one end of said rod terminating in a T head having a hole therethrough, a reduced neck near the other end of said rod, and a head at said latter end terminating in a longitudinally extending eccentric locking pin, the latter being located out of alinement with the longitudinal axis of said piston rod. 70 75

6. As an improved article of manufacture, inside toggles having portions thereof interlocking when assembled and provided with smooth tapered extensions, which when assembled have the form of a truncated cone, said toggles being provided with seats 42, 44 and 45 and one of said toggles having 80 a terminal recess 77 adapted to receive an interlocking eccentric pin carried by a piston rod. 85

7. As an improved article of manufacture, the herein-described outside toggles having 90 curved arms and interlocking hooked ends, dowel pins and seats common to said toggles, the latter having smooth tapered extensions which when assembled have the form of a truncated cone, said toggles having the seats 95 61, 63 and 64 for the reception of the end of a piston rod and one of said toggles having the recess 76 for the reception of an interlocking eccentric pin carried by a piston rod. 100

8. The combination of pistons, means for controlling the reciprocations thereof, piston rods connected to said pistons and threaded at a point intermediate their ends, a crank shaft, toggles engaging said piston rods and carried by said crank shaft and provided with smooth tapered extensions, and a binding nut threaded upon each of said piston rods and provided with a conical internal seat frictionally engaging said tapered extensions. 105 110

9. In a machine of the character stated, the combination of pistons, means for controlling the reciprocations of said pistons, a crank shaft, piston rods pivotally connected to said pistons, toggles engaging said crank shaft, said toggles having tapered smooth extensions, interlocking devices common to said piston rods and toggles for preventing improper rotation of said rods and 115 pistons, and binding nuts each having one portion in threaded engagement with said piston rod and its opposite portion in frictional engagement with the tapered extensions of said toggles. 120 125

10. The combination of a pair of pistons, means for controlling the reciprocations of said pistons, a pair of piston rods pivotally attached thereto and exteriorly threaded intermediate their ends, a crank shaft, inside 130

and outside toggles for said crank shaft, said piston rods having eccentric terminal members interlocking with recesses in said toggles, tapered extensions on said toggles, and binding nuts in threaded engagement with said piston rods and provided with conical seats engaging the tapered extensions of said toggles.

11. In a device of the character stated, the combination of pistons, means for controlling the reciprocations of said pistons, piston rods pivotally connected thereto, each of said piston rods having a portion thereof intermediate its ends threaded, a reduced neck near one of said ends, and a head at said latter end terminating in a longitudinally extending locking pin, the latter being located out of alignment with the longitudinal axis of said rod, toggle members having tapered extensions and recessed for the reception of said locking pin, and binding nuts having tapered internal seats engaging said tapered extensions, said binding nuts being in threaded engagement with said piston rods.

12. In a device of the character stated, pistons, means for controlling the reciprocations thereof, a crank shaft, toggles for the latter having smooth tapered exterior extensions, piston rods common to said toggles and pistons, and binding nuts frictionally engaging said tapered extensions and in threaded engagement with said piston rods.

13. In a device of the character stated, pistons, means for controlling the reciprocations thereof, a crank shaft, toggles for the latter having smooth tapered exterior extensions, piston rods common to said toggles and pistons, and binding nuts frictionally engaging said tapered extensions and in threaded engagement with said piston rods, in combination with means for preventing rotation of said piston rods with respect to said toggles.

14. In a device of the character stated, pistons, means for controlling the reciprocations of said pistons, piston rods pivotally connected thereto, and having threaded portions intermediate their ends, outside toggles having recesses in their juxtaposed portions interlocked with said piston rods, said toggles having tapered smooth extensions, a

binding nut having a threaded portion engaging the threaded portion of its piston rod, the latter having an eccentric terminal locking pin engaging a recess in one of said toggle members, a crank shaft, inside toggles engaging said crank shaft and carrying said outside toggles, said inside toggles having their piston rod interlocked therewith and provided with smooth tapered extensions, and a binding nut engaging the threaded portion of said latter piston rod and having internal conical walls engaging said latter tapered extensions.

15. In a device of the character stated, a piston rod, toggle sections engaging one end of the piston rod, and means to prevent the rotation of the rod on its longitudinal axis including an element interlocking with one of said toggle sections and arranged eccentrically with relation to the piston rod.

16. In a device of the character stated, a piston rod, toggle sections engaging one end of the piston rod, one toggle section having a longitudinal recess formed therein, and an eccentric locking pin secured to the end of the piston rod and entering said longitudinal recess.

17. As an improved article of manufacture, inside toggles, provided with smooth tapered extensions, which when assembled have the form of a truncated cone and are adapted to be frictionally engaged by a binding nut, the juxtaposed portions of said toggles having seats therein which are adapted to be interlocked with the contiguous portion of a coacting piston rod.

18. As an improved article of manufacture, outside toggles having curved arms, outer interlocking hooked ends and smooth tapered extensions, which when assembled have the form of a truncated cone, and are adapted to be frictionally engaged by a binding nut, the juxtaposed portions of said toggles having seats therein adapted to be interlocked with the end of a coacting piston rod.

LEWIS SYKES.
